UNITED STATES PATENT OFFICE.

JOSEPH LODATO, OF OGDEN, UTAH.

SHIP-SALVAGING DEVICE.

1,375,055.

Specification of Letters Patent. Patented Apr. 19, 1921.

Application filed June 5, 1920. Serial No. 386,675.

To all whom it may concern:

Be it known that I, JOSEPH LODATO, a citizen of the United States, residing at Ogden, in the county of Weber and State of Utah, 5 have invented new and useful Improvements in Ship-Salvaging Devices, of which the following is a specification.

The invention contemplates the utilization of a series of inflatable bags at each side 10 of a vessel or ship, which under normal conditions are deflated and stowed in compact form along the outboard rail of the ship's side, and, when required, may with facility be lowered partly below the water level and 15 there inflated to afford a buoyant support for an injured ship to prevent sinking, and may with equal facility be adapted for use in raising sunken vessels and in connection with dry docks, for repair work.

20 With the above ends in view the invention consists in certain novel combinations and arrangements of parts including mechanism whereby the inflatable bags are positively lowered and subsequently raised in 25 similar manner and in operating means for such mechanism, together with means for inflating the bags, all controlled from a central and single station, and further in features of construction as will be hereinafter 30 pointed out and claimed.

In the accompanying drawings I have illustrated one complete example of the physical embodiment of my invention in which the parts are combined and arranged 35 according to the best mode I have thus far devised for the practical application of the principles of my invention.

In the preferred form of the invention as illustrated in the drawings—

40 Figure 1 is a view in side elevation of a vessel equipped with my salvaging device, the inflatable bags being shown in normal position stowed away at the outboard side of the ship rail.

45 Fig. 2 is a similar view of a ship with the bags inflated and in buoyant position.

Fig. 3 is an enlarged sectional view showing transversely a portion of the ship's side together with one of the inflated bags in 50 operative position, together with the hoisting and lowering mechanism and connections for inflating the bag.

Fig. 4 is a view from the outboard side of the vessel showing the parts of Fig. 3.

55 Fig. 5 is a diagrammatic plan view show-

ing the equipment and connections of the invention.

Fig. 6 is a detail view showing means for holding the operating shafts.

For a general understanding of the equipment of the invention, reference may be had to Fig. 5 of the drawings wherein the diagrammatic showing of the invention is illustrated in conventional form, it being understood that the equipment may be installed at 65 the most convenient and desirable parts of the vessel, which is indicated by the letter S.

For actuating the operative parts of the salvaging equipment I employ an air compressor 1, which is connected with two series 70 of air reservoirs 2 and 3, ranged along the inboard side of the vessel at suitable locations, and each of the reservoirs is connected with an inflatable bag as 4 by a flexible tube or hose 5, the hose being attached 75 to the reservoir, and the reservoir in each instance being connected to the compressor as by a pipe 6. The admission of motive fluid to the reservoirs is controlled from a central point 7, and through this control 80 device the bags may be inflated from their respective reservoirs.

In connection with the means for lowering and raising the bags preparatory to inflation and subsequent to deflation a series 85 of pneumatic motors 8 is employed, one for each bag, and each motor is designed to revolve a shaft 9 to which it is operatively connected, and the motors have pipe connection to the air compressor as indicated 90 at 10, and their operation is controlled from the device 11.

The deflated bags are designed to be lowered through the instrumentality of the air motors, to position, then to be initially inflated from the reservoirs 2 from a control device 12, and completely inflated by motive fluid passing through the reservoirs under pressure from the air compressor 1. Thus 95 the entire equipment is controlled and operated, as by the helmsman, from a single station through the three control devices 7, 11, and 12.

The inflatable bags 4 are each preferably made up of an inner rubber tube or casing 105 13 which of course is air tight, and covered with a casing of fabric 14, and an outer casing 15, the whole being encircled by cables 16 preferably of steel and laid thereon as a reinforcing net-work to provide flex- 110

ible walls for the inflated bag in order that it may be folded or compressed into compact form when not in use, and to sustain the interior pressure of air when the bag is inflated.

5 The reservoir 2 and the bag 4 are connected by the flexible pipe or hose 5 attached respectively at 17 and 18 to the bag and reservoir, the reservoir being at the inboard 10 side of the vessel as in Fig. 3, and the bag at the outboard side, and the flexible hose 5 passing through an opening in the side of the vessel provided for the purpose.

15 Each bag is provided with mechanism for positively lowering it to the water level for inflation and with similar mechanism for raising the bag to elevated position when not in use, the mechanism being actuated from the shaft 9 through the pneumatic motor 8 connected thereto. The several devices 20 adapted for use with each bag for lowering and raising the same are arranged in series, a suitable number being provided for each bag in order that it may be manipulated 25 with facility and despatch, and the series of devices for each bag is actuated simultaneously from the respective shafts 9. The shafts 9 are mounted along the rail of the ship or vessel and each unit or series of devices comprises pairs of drums 13' and 14' 30 fixed to revolve with the shaft as indicated in Fig. 4 over which may be wound or unwound the cables 15' and 16' respectively. These cables are wound on their respective 35 drums in opposite directions in order that the cable may be wound on one drum while the cable on the other drum is being unwound, and vice versa. The cable 16' passes from its drum over a guide sheave or 40 grooved pulley 17' and thence down the side of the ship around a guide roller 18 journaled in a bracket 19 riveted to the outside of the hull of the vessel beneath the water line, and the looped end 20 of the cable is 45 attached to an eye 21 of a metallic bracket 22 fixed to the bag 4. It will be apparent that the function of this cable is to draw down, beneath the water line, the deflated bag, and the series of draw cables is disposed 50 along the side of the ship in suitable numbers, in order that the bag may with uniformity and despatch be drawn downwardly to proper position. The lowering of the bag to position is accomplished by the rotation of the shaft 9 through its pneumatic motor.

55 The bag is drawn upwardly by the action of a complementary series of cables 15' which are hoist cables passing from the 60 drum 13' over the guide pulley 23 journaled on a davit 24 fixed to the ship or vessel and thence passing around the bag and through the eye 21 of the bracket 22 on the bag. One end of this cable 15' is attached at 25 to the 65 davit and just beneath this attached end is

arranged a cross arm 26 fixed to the cable and extending equidistant at the sides thereof. From the respective ends of the cross arm are extended a pair of ropes 27, 28 which converge and are attached or spliced 70 to the cable at 29, to form a stop or abutment for the eye 21 to engage. Thus, when the deflated bag is to be hoisted from lowered position, the shaft 9 is turned clockwise to unwind the cable 16', and wind the cable 15' on its drum 13', and the bag is bodily hoisted by the series of looped cables 15' 75 until the eye 21 encounters the splice or joint 29 on cable 15'. The continued winding of the cable 15' causes the bag to be 80 rolled by the action of the branch cords or cables 27, 28, thus compactly reducing the bulk of the deflated bag in order that it may be stowed away at the rail of the ship to occupy the smallest possible space.

85 It will be understood that the several draw cables and the complementary hoist cables perform their functions synchronously and in this manner the deflated bag may positively be lowered while at a uniform level, and may also be positively hoisted up the side of the ship while at uniform level, thus providing a facile and smooth working apparatus for lowering and raising the bag.

90 The flexible air pipe or hose 5 between the air reservoir and buoyant bag is of course extended when the bag is lowered, and when the bag is raised or hoisted to the rail of the ship the hose or pipe is coiled or 100 compactly folded between the reservoir and the bag and arranged in ship-shape fashion to preserve its durability and reduce wear thereon.

95 In operation, in case of emergency when the proper signal is given, the helmsman, or officer in charge starts the air motors 8 from the control device 11 at the central station, to revolve the shafts 9. The shafts revolve their respective pairs of drums, unwinding 110 the hoist cables and winding the draw cables to pull down the deflated bags. The initial motion of the bags is to unroll from their compacted form, and they are then drawn directly down to the water level, the shafts 115 being held in stationary position by means of pawls 30 and ratchet wheels 31 on the shafts, or other suitable devices may be employed to hold the drums and their cables stationary after the required position of 120 the bags has been reached. The deflated bags are now ready for inflation and the reservoirs 2 are opened for communication with the bags by manipulating the control device 12 for the reservoirs providing an 125 initial supply to the bags, which is then supplemented from the air compressor under control of the device 7 which provides air under pressure to the bags until they have been filled to their capacity. In this man- 130

ner the two series of bags may be filled to buoyancy with air in order to afford a support for the damaged ship and to maintain it afloat.

5 After having performed their required functions, pressure is released from the bags under control of the devices 7 and 12, and the bags are deflated and ready to be hoisted to inoperative position. The shafts 9 are 10 now revolved in reverse direction, under power from the air motors 8, and the drums 13' and 14' are turned to wind the hoist cable 15' and unwind the draw cable 16', with the result that the deflated bags are elevated bodily and with a uniform motion. When the splice or abutment 29 encounters the eye 21 on the bag, the passage of the cable through the eye is thus stopped, and from this point, as the winding of the cable 20 15' continues, the two ropes 27 and 28 are also caused to wrap around the deflated bag with the result that the bag is rolled or wrapped into small compact form, and by the time the bag reaches the cross arm 26 the 25 two ropes have been tightly wrapped about the bag as in Fig. 1 and the bags are stowed away at the outboard side of the ship's rail.

Under control of the devices at the central control station the bags may be lowered 30 and inflated, and subsequently deflated and hoisted to position with rapidity and convenience. The number and size of the bags used may be determined by the size and other factors of the ship to be equipped, and 35 while I have not illustrated in detail all the devices and elements of a complete installation, the essential parts of the equipment are herein illustrated and described.

Having thus fully described my invention, 40 what I claim and desire to secure by Letters Patent is—

1. In a ship salvaging device, the combination with an inflatable bag, of operative means for positively drawing the bag to operative position at the water level, means for inflating the bag, means for deflating the bag, means for hoisting the deflated bag to inoperative position and for wrapping the bag upon itself in compact form.

50 2. In a ship salvaging device, the combination with an inflatable bag, of means for positively drawing the bag to operative position and for inflating said bag, means for deflating the bag, means for elevating the bag, and means co-acting with said elevating means for wrapping the bag upon itself and stowing the bag, as described.

3. In a ship salvaging device, the combination with an inflatable bag, of an operating shaft and a pair of drums thereon, oppositely wound cables on said drums operatively engaging said bag, and means for

actuating said shaft in reverse directions to successively lower the bag to buoyant supporting position and to elevate and roll said 65 bag with one of said cables to normal position.

4. In a salvaging device as described, the combination with an inflatable, normally elevated bag, of a reversible shaft and a pair 70 of drums thereon, oppositely wound cables on said drums operatively engaging said bag, means for operating said shaft to successively lower the bag to buoyant supporting position and to elevate said bag to normal 75 position, and means for wrapping said bag upon itself to compact form as it approaches normal position.

5. In a salvaging device as described, the combination with an inflatable buoyant bag, 80 of a reversible shaft and a pair of drums thereon, oppositely wound cables on said drums operatively engaging said bag, wrapping ropes on one of said cables, and means for operating said shaft to successively lower 85 the bag to buoyant supporting position and to elevate said bag whereby the bag is wrapped upon itself to compact form as it approaches its normal elevated position.

6. The combination with the bag as described, of a shaft and drums thereon, a draw rope on one drum connected to the bag, a hoist rope adapted to wind in opposite direction on the other drum and passed around the bag, a transverse arm on the 95 hoist rope, and wrapping ropes attached at the ends of said arm and to the hoist rope for the purpose described.

7. The combination with a bag as described, of a draw cable having a guide-support and attached to the bag, a hoist cable passed around the bag and through a member thereon, means for winding the cables in opposite directions, and means on the hoist cable for wrapping the bag as the latter is 105 elevated to inoperative position.

8. In a salvaging device the combination with an inflatable, buoyant bag carried by a ship, of a draw cable extended down the outside of the ship, a guide device on the ship for said cable and an eye-bracket on the bag to which said cable is attached, a hoist cable passed around the bag and through said eye-bracket, means for operating said cables in opposite directions, a davit for 110 supporting one end of the hoist cable, a cross arm on the hoist cable near said davit, a pair of wrapping ropes attached at the ends of the cross arm, and said ropes attached to said hoist cable to form an abutment for 115 engagement with the eye-bracket, for the purpose described.

JOSEPH LODATO.
